JOSEPH TRIULZI, OF LOS ANGELES, CALIFORNIA, ASSIGNOR TO BRALY MANUFACTURING COMPANY, OF LOS ANGELES, CALIFORNIA, A CORPORATION OF CALIFORNIA.

DRYING MACHINE.

Application filed July 12, 1927. Serial No. 205,102.

This invention has to do generally with drying machines, and is particularly well adapted for embodiment in machines for drying material such as macaroni, though it is to be understood it is in no way limited to this particular use.

However, due to its peculiar effectiveness in the drying of macaroni, I have chosen to describe the machine as put to this use. From the understanding gained from this discussion, those skilled in the art will readily appreciate the diversified use to which a machine embodying the invention may be put. It may be stated at the outset, that the machine is not intended for drying long strips of macaroni, but rather, so-called "elbows" or relatively short lengths of macaroni, the length varying from a fraction of an inch to several inches.

As the macaroni comes from the forming dies and cut-off mechanism, it is in moist, plastic state, and in order to secure a final product of superior quality, it is necessary that the macaroni be dried evenly and comparatively slowly. The drying afforded by this machine is what is termed the initial drying, the final drying being accomplished in drying rooms.

As differentiated from the usual bath system of initially drying the macaroni, where the macaroni is merely spread on trays and deposited in a heated chamber, my machine is adapted to keep the macaroni moving during the initial drying in such a manner that a continuous flow of the material is being dried as rapidly as it comes from the forming machine, and as the material passes through the machine it is constantly rolled or tumbled about so that all sides of the individual pieces are exposed to the drying medium, thus insuring even treatment.

Not only does a superior product result from this continuous feeding of the material, but considerable economic advantage is gained due to the fact that it requires but a single attendant for the machine and that a large bulk of material is being continuously dried without the necessity of it being disposed on drying trays and then transported into drying chambers with the attendant loss of time and requirement of constant labor on the part of several operators.

Generally, I accomplish the above by the

provision of a drum having a double peripheral wall and means for advancing the macaroni or other articles to be dried between the walls and axially of the drum. This progress of the macaroni between the drum walls is comparatively slow, the time consumed being such that the draft of air passing through the perforated drum walls from within has ample time to have the proper initial drying action on the macaroni. During its passage between the walls, the individual pieces of macaroni are rolled or tumbled about in a manner exposing all their superficial surfaces to the action of the drying air.

The device may also be considered as a drum having a plurality of compartments extending longitudinally thereof, with means for advancing the macaroni through said compartments, the drum being rotatable in order to bring the compartments successively into registration with a feeding chute so the charging of the drum may be continuous.

While the invention may be considered as broadly covering the provision of a rotatable drum with means for advancing material through compartments extending longitudinally thereof, irrespective of the particular advancing means, a further and preferred feature, though not an essential, is the provision of advancing means operable by virtue of rotation of the drum, and as a still further preferable, though not necessary, feature, this advancing means may be stationary with respect to the drum. The last-named feature is advantageous not only by reason of the consequent reduction in number of parts and hence increased simplicity of the machine, but are also in that there is less likelihood of damage to the macaroni as it passes through the machine. In other words, were the advancing means to be movable with respect to the compartment walls, it will be appreciated that damage or mutilation of the macaroni might result by reason of being caught between the stationary and moving parts. On the other hand by fashioning the advancing means in such a manner that it is fixed with respect to the drum, there is no relative movement of parts within the compartments, and consequently there is no danger of the macaroni being drawn in between parts and thereby mutilated.

Other objects and novel features of the in-

vention will be set forth in the accompanying detailed description, reference being had to the accompanying drawings, in which:

Fig. 1 is a side elevation of a machine embodying my invention;

Fig. 2 is a section on line 2—2 of Fig. 1;

Fig. 3 is a view of Fig. 1 as viewed from the right thereof;

Fig. 4 is a view of Fig. 1, as viewed from the left thereof;

Fig. 5 is a section on line 5—5 of Fig. 2;

Fig. 6 is an enlarged, fragmentary section on line 6—6 of Fig. 1;

Fig. 7 is a fragmentary, perspective view 15 of one of the material advancing compartments;

Fig. 8 is an enlarged, fragmentary view of the delivery or discharge end of the drum;

Fig. 9 is a section on line 9—9 of Fig. 8;

Fig. 10 is a plan view of a modified form of housing defining a material advancing compartment;

Fig. 11 is an enlarged section on line 11—11 of Fig. 10;

Fig. 12 is a sectional view, partly in elevation, of a variational embodiment of the invention;

Fig. 13 is a reduced section on line 13—13 of Fig. 12; and

Fig. 14 is a fragmentary section through another variational form of means for advancing material through the machine.

Numeral 10 designates generally a drum mounted for rotation between stationarily mounted end frames 11 and 12. The drum includes a skeleton framework 13 of cylindrical form, made up of end spiders 14, 15, and longitudinally extending bars 16, secured to said spiders at 17 and thus tying them together.

Spiders 14 and 15 have outwardly extending, axial hubs 18 and 19, respectively, these hubs being tubular and being journalled in boxes 20 and 21 on frames 11 and 12, respectively.

Shaft 22, coaxial with the drum, is journalled near one end 23 in the bore of hub 18, and the other end 24 is journalled in the hub 25 of wormwheel 26, which wheel-hub 25 is keyed at 27 to spider-hub 19. It follows that rotation of wheel 26 gives angular movement to spider 15, and hence to the drum, while shaft 22 is capable of rotation with respect to the drum.

The drum is rotated by motor M through belt 28 and the reduction gearing generally indicated at 29 and of which wormwheel 26 is a part. The motor speed and drive connection is such that the angular velocity of the drum is comparatively low, for instance, $\frac{1}{2}$ R. P. M., though it will be understood the speed here given is in no way to be considered as limitative.

Shaft 22 is adapted to be revolved at comparatively high speed, for instance, 800 R. P. M., by motor M', there being a pulley

and belt connection 30 between the motor and shaft. The shaft is adapted to drive one or more fans positioned within the drum. While the number and type of fans are optional, I have here illustrated two fans F and F', each consisting of a pair of spiders 31 secured to shaft 22 and connected by fan blades 31a. These fan blades are preferably inclined longitudinally with respect to the axis of the drum, so they are adapted to draw air in from the ends of the skeleton frame between the arms of the frame spiders and to force said air substantially radially outward towards, and, as will be hereinafter described, through the inner and outer drum walls.

Thus it will be seen that the drum is adapted to be rotated comparatively slowly while the fans are driven with comparatively great speed, the differential in angular velocity being allowed by reason of the hub bearings 85 hereinbefore described.

Secured to bars 16 as at 16a (Fig. 8) are a plurality of radial, angularly spaced partition plates 32, which define the sides of compartments 33, said compartments extending 90 longitudinally from end to end of the drum. Within these compartments are means for advancing material from one drum-end to the other, and while my broader claims contemplate any suitable means to accomplish this 95 advance, it is preferable that said means be operated by virtue of drum rotation, and also that the means be stationary with respect to the drum. Even with the last two conditions existing, the advancing means may vary in 100 form to a considerable degree, but such variations are within the spirit and scope of the broader claims appended hereto.

I will first describe the advancing means shown in Fig. 2, and later will set forth 105 several variations thereof. In the embodiment shown in Fig. 2, the material advance is gained by virtue of the formation of the inner and outer defining walls of compartments 33, and said walls may generally be described as of "sawtooth" formation, the points of the teeth of one wall being staggered or out of radial alignment with respect to the teeth of the other wall. Thus, the inner wall 34 of a given compartment has portions 35 inclined with respect to the axis of the drum, and portions 36 which are substantially at right angles to said axis. The outer wall 37 has oppositely inclined portions 38 and 39. The adjacent portions of inner wall 34 define pockets 40, while the adjacent portions of wall 37 define pockets 41. It will be noted that the walls thus divide, in effect, each compartment 33 into a series of inner and outer pockets, the bottoms of the inner pockets being staggered or out of radial alignment with respect to the bottoms of the outer pockets.

It will be understood that the indicated inclination of the pocket walls is not limitative,

for such inclination may be varied within quite a wide range without rendering the device inoperative; it is only necessary that the walls of the inner and outer pockets be so 5 relatively arranged and so inclined that given articles will, at certain periods of operation, gravitate thereover, and that the bottom of a given pocket is in radial alignment with an article-advancing, inclined wall of the 10 substantially opposite pocket. Thus, take the typical case of adjacent inner pockets A and B and the substantially opposite outer pockets C and D. The walls 35 of pockets A and B and the walls 38 of pockets C and D may be 15 considered as "advancing walls", it being noted that the advancing walls of the inner and outer pockets incline oppositely, and that the bottom 42 of pocket A lies to the right of bottom 43 of pocket C, that pocket bottom 20 43 lies to the right of bottom 44 of pocket B, and that bottom 44 lies to the right of bottom 45 of pocket D. This arrangement may be expressed otherwise by stating that the bottom of a given inner or outer pocket lies 25 intermediate the ends of an advancing wall of a substantially opposite outer or inner pocket.

With the above arrangement in mind, it will be well to discuss at this point the 30 advance of material longitudinally of the drum, disregarding for the time being the particular means employed for introducing the material to the compartments. In this discussion, pockets at the lower part of the machine 35 and diametrically opposite pockets A, B, C and D, will be given similar, but primed reference characters, it being assumed that 180° angular movement of the drum brings pockets A, B, C and D to the positions indicated by 40 characters A', B', C', and D' respectively. It will of course be obvious that a single rotation of the drum bodily rotates a given compartment through 360°.

Assume that material S—macaroni, for instance—lies within the pocket A, and that the 45 drum starts to rotate. As the drum rotates in a counter-clockwise direction, as viewed in Fig. 3, material S drops from pocket A onto advancing wall 38 of pocket C, and by the time the drum has rotated through 180°, the material will have gravitated over said advancing wall 38 to the bottom 43^a of pocket C in its position of C'. As the drum continues rotating, the material drops from 50 pocket C onto the advancing wall 35 of pocket B, and by the time the drum has completed a single revolution the material will have slid down this wall 35 into the bottom 44 of pocket B.

60 It will thus be seen that a single rotation of the drum has advanced the material from one pocket to the next, and consequently that continued rotation of the drum slowly but regularly advances the material from end to 65 end of the compartment or of the drum.

During this passage the material is rolled or tumbled about in a manner to expedite drying and to expose all its superficial area to drying action.

Main dependence is had for this drying action on the fans F and F', some or all of the inner and outer wall portions being perforated as at P to allow the passage of fan-driven air substantially radially through the compartments. However, this draft is 75 not sufficiently strong to blow the material out of the pockets.

I will now describe the preferred means for feeding the material to the drum compartments. At the right hand end of the 80 machine, as viewed in Fig. 1, the compartment ends are closed by a ring-plate 46 stationarily mounted on member 47 secured to end frame 12 at 48. However, ring-plate 46 has at its lower side an opening 49 in register 85 with one or more of the compartments and a feeding chute 50 is secured at its delivery end 51 to plate 46 and opens to aperture 49.

While the material to be dried may be advanced through chute 50 and thereby delivered to the entrance mouths of the compartments in any suitable manner, I prefer to provide a blower 52^a having a delivery duct 52 opening to chute 50 at 53, this blower being adapted to eject the material from chute 50 95 and force it into the entry mouths 33^a of the compartments. While this is not essential, I also prefer to provide an auxiliary blower duct 54 leading from duct 52 and opening through plate 46 to a plurality of entry 100 mouths 33^a, as at 55 (Fig. 2). The auxiliary duct discharge is angularly spaced at approximately 90°, though this angle is not controlling, from the discharge mouth of the main duct 52 and in the direction of drum rotation. The auxiliary duct is adapted to give an additional blast which serves to advance into the compartments any material 105 which may not have been forced far enough thereinto by the main duct.

At the left hand end of the machine (as viewed in Fig. 1), the compartments are closed by inclined advancing walls 38^b, except for the relatively restricted delivery or discharge mouths 56. A discharge chute 57 110 is supported from frame 11 as by braces 58, and the chute is of a width, as viewed in Fig. 4, to take in a plurality of discharge mouths. However, in order that material may not be finally discharged until it has been carried up 115 to the mouth of the discharge chute, I prefer to provide catchers 59 (Figs. 8 and 9) which are in the form of angles secured to the extensions 32^a of partition plates 32. These angles extend partially across each pocket in 120 the direction of drum rotation and serve to catch such material as may pass out of the discharge mouths prior to the time said mouths register with the discharge chute.

It will be noted that the assembly above 130

described may be considered as a rotatable drum having a double wall (inner wall 34 and outer wall 37), the two walls being radially spaced, and means for advancing material longitudinally of the drum and between said walls. The fan may be described as means provided for passing air or a drying medium through the space between the two drum walls, the direction of air passage, preferably, though not necessarily, being substantially radial.

In Figs. 10 and 11 I have shown a somewhat simpler method of forming the compartment advancing walls. In this case the inner wall 34^a is made up of a length of screen drawn over pins 60, which extend between adjacent partition plates 32, while outer wall 37^a is made up of a strip of screen drawn over pins 61 which extend between plates 32. It will be seen that the formation of the pockets is substantially the same as above described in connection with the other figures, and that rotation of the compartment through drum rotation causes advance of material through 25 the compartment in the manner described above.

In Figs. 12 and 13 I have shown another variation wherein compartments 32^a are defined by cylindrical tubes 62 arranged in a ring about the periphery of the drum, each tube being made up of screening. The means for advancing material through these compartments, which correspond with compartments 32, are worms or spirals 63, supported at their opposite ends 64 in spiders 14 and 15. The spirals may also be considered as supporting means for the tubes. The rest of the machine may be substantially the same as that described above.

It will be seen that as the drum rotates, the spirals or worms, which are preferably held stationary with respect to the drum, serve to advance the material longitudinally through compartments 32^a, the delivery to the compartments and discharge therefrom being generally similar to that previously described. In this case, however, the material, instead of being dropped from one compartment wall to another, merely rolls about the peripheries of the compartment walls, thus exposing the material fully and evenly to the effect of the drying medium.

In Fig. 14 I have shown another variation, the arrangement being substantially like that shown in Fig. 12 except that the central part of the spiral is omitted. In other words, for spiral 63 is substituted a spiral flange 65, secured in any desired manner to screen 62. As a means for stiffening the screen tube and

holding it properly in position I provide a plurality of rods 66, spot welded or otherwise suitably secured to screen 62, and terminally held at 67 by spiders 15. It will be apparent that the spiral flange advances the material through the compartment 32^a, just as it is adapted to be fed through compartment 32^a by worm 63 (Fig. 12).

In the variations shown in Figs. 12 and 14 it will be seen that the device may still be considered as a drum having a double wall, the walls being radially spaced, with means for advancing material longitudinally of the drum between said walls, and that the fans disposed within the drum are adapted to direct air or a drying medium through said walls and hence through the compartments defined thereby.

It will be understood the drawings and description are to be considered merely as illustrative of and not restrictive on the broader claims appended hereto, for various changes in design, structure and arrangements may be made without departing from the spirit and scope of said claims.

I claim:

1. In a device of the character described, a rotatable drum having a plurality of compartments extending longitudinally in the direction of the axis of rotation of the drum, each compartment being defined by relatively fixed and apertured walls, means for rotating the drum, means within each compartment for feeding material longitudinally therethrough, said compartments being grouped in a circle about and being radially spaced from the drum axis, and means in the drum inside the compartment group for forcing air radially outward through the apertured walls of the compartments.

2. In a device of the character described, a rotatable drum having a plurality of compartments extending longitudinally in the direction of the axis of rotation of the drum, each compartment being defined by relatively fixed and apertured walls, means for rotating the drum, a spiral within each compartment for feeding material longitudinally therethrough, said compartments being grouped in a circle about and being radially spaced from the drum axis, and means in the drum inside the compartment group for forcing air radially outward through the apertured walls of the compartments.

In witness that I claim the foregoing I have hereunto subscribed my name this 31 day of May, 1927.

JOSEPH TRIULZI.
